UNITED STATES PATENT OFFICE

FRIEDRICH OTTENSTEIN, OF NUEREMBERG, GERMANY

TRACK FOR TOY RAILWAYS

Application filed June 5, 1931, Serial No. 542,437, and in Germany June 10, 1930.

In the known crossings and points for the tracks of toy railways it has been found that the toy locomotives and wagons easily become derailed and that the vehicle undercarriages are subjected to shocks, as the guides for the wheels at the intersections and crossing places are not up to the requirements and have too much clearance. In electrically driven toy railways these intersections are the cause of many short-circuits which in automatically reversing locomotives result in the locomotive coming to rest and involve constant switching over. This defect is put down to the circumstance that in the mass production of these track sections on the one hand the pin and soldered connections between the track substructure and the rails cannot be made with sufficient accuracy and on the other hand that the insulation of one part from another is difficult to carry out. Experience has shown more especially that coating of insulation on the inner side of the wheel does not last, so that the sliding contact and the badly insulated wheels of the locomotive both at the same time make contact with the same piece of rail, thereby causing a short circuit of the electric current.

These disadvantages are overcome according to the invention by the insertion between the rail joints of the tracks at the crossings or points of solid fitting pieces. These fitting pieces, as is known in the case of complete connecting pieces for points and crossings, have incisions in which the rails to be joined up can be inserted in such a manner that they form a continuation of the raised parts of the fitting pieces, which correspond to the general run of the rails.

According to the invention the fitting pieces consist of a separately made, pressed piece of insulating or other material, which is adapted to be screwed to and unscrewed from a sleeper or other part of the track replacing the latter. As the fitting pieces can be pressed very accurately, they make possible a very accurate transition at the crossings of the rails. They provide for the vehicle wheels rolling over these crossing places an almost continuous guide and in-

sulate from one another efficiently the parts which carry current but do not belong to one another electrically. There is the further advantage that they can be easily installed into the sections of track to be put together by the playing child, and can thus be used as a constructional toy element, but are also suitable for insertion in rail sections supplied by the factory as a complete unit.

In the accompanying drawings various constructional examples of the invention are shown as applied to a switch and a crossing,

Figs. 1 and 2 representing a switch and a crossing seen from above, to a reduced scale with diagrammatically shown securing members,

Fig. 3 a plan view of a fitting piece lying immediately behind the switch blades, which is mounted on a toy sleeper,

Fig. 4 the fitting piece according to Fig. 3 alone without rails,

Fig. 5 the fitting piece according to Fig. 3 in section along line A—A of Fig. 4,

Fig. 6 the fitting piece according to Fig. 4 seen from below,

Fig. 7 a plan view of the middle part of a rail crossing,

Fig. 8 the fitting piece belonging to the middle piece according to Fig. 7 alone without rails,

Fig. 9 the fitting piece according to Fig. 8 in section along line B—B,

Fig. 10 a fitting piece for the intersection of the two inner rails of the crossing or the crossing plate of the switch, seen from above,

Fig. 11 the fitting piece according to Fig. 10 without rails,

Fig. 12 the fitting piece according to Fig. 11 in section along line C—C of Fig. 11, and

Figs. 13 and 14 a supplementary piece to be disposed behind the fitting piece according to Fig. 11 in plan view and end view.

According to Fig. 1, from a straight track 1, 1a, 1b a curved track 2, 2a, 2b branches off. Immediately behind the switch blades 3, 4 is a fitting piece 5 of insulating material, such as steatite, hard rubber, celluloid, vulcanized fibre or the like material. Another fitting

piece 6 is provided at the place of intersection of the two inner rails 1a, 1b and 2a, 2b.

The fitting piece 5 to be fixed by means of screws 5a (Fig. 3) on a sleeper 7 consists of an elongated plate, the end edges 8, 9 of which (Fig. 4) extend parallel to the rails 1, 2 and form the abutments for the latter, when the rails are pressed by the clips 10 provided on the sleeper 7 by means of the screws 10a against the fitting piece 5 (Fig. 3). Between the blades 3, 4 and the rails 1a, 2a are disposed so as to be flush with the said parts 3, 4, 1a, 2a, two short bars 11, 12 projecting upwards from the plate 5 and two incisions 13, 14 behind the said bars (Figs. 4, 5, 6). The bars 11, 12 are of such a shape that with the blades 3, 4 and the rails 1a, 2a forming their forward and rearward continuation they form a practically jointless smooth and uninterrupted track. The incisions 13, 14 are made such that the webs and flanges of the rails 1a, 2a can be tightly fitted into them. On the under side of the plate 5 is a groove 15 for the reception of a live rail fish-plate, which in electrically operated railways are inserted between the plate 5 and the sleeper 7 and are held in position by the screw 5a. There are further provided on the under side of the plate 5 two recesses 16 which act as bearings for the pivot pins on the switch blades.

For assembling the switch the plate 5 and the clips 10 are first screwed loosely on the sleeper 7 and the blades 3 and 4 inserted, whereupon the rails and the rail ends are pushed in and finally the four fixing screws 10a and 5a are tightened.

According to Figs. 2 and 7 two straight tracks 17—17f and 18—18f cross over a broad middle sleeper 19. The fitting piece 20 which is inserted between the crossing rail sections has side edges 21 forming obtuse re-entrant angles (Fig. 8), raised parts 22, 23, 23a, 24 and incisions 25, 26 at the end sides. The incisions 25, 26 are flush with the raised parts 23a, 23 lying next to them and are of such a shape that the rail pieces 17a, 18a and 17e, 18e can be pushed into them so as to fit tightly. Furthermore, the raised parts 23, 23a and 24 are of such a shape that they constitute pieces of track forming a continuation of the said pieces of rail. The raised parts 22 form an inner guide for the vehicle wheels running over the crossing. The rails 17, 18 and 17e, 18e are pressed by clips 27 provided on the sleeper 19 and by means of screws 27a against the side edges 21, which at the places in question recede with respect to the raised parts 24 by the width of the rail.

The parts to be mounted on the sleeper 19 are fixed in a similar way to the switch parts shown in Figs. 3 to 6. The pressed piece 20 is fixed by screws 28 to the sleeper 19.

Figs. 10 to 14 show a fitting piece 6 for the crossing of two inner rails, which can be used

both for switches and for crossings. This fitting piece 6 which is fixed by a screw 29a to a sole-plate 29, is provided with incisions 30, 31, 32, 33 (Fig. 11) and raised parts 34, 35 which extend at an obtuse angle and supplement the track and a wedge shaped block 36. Into the incisions 30 to 33 either the rails 1a, 2a, 1b, 2b of the switch according to Fig. 1 or the rails 17f, 18f, 17e, 18e or 17a, 18a, 17b, 18b (Fig. 2) are inserted. For the sake of stability a small fitting wedge piece 37 is inserted in each case behind the fitting piece 6 and is fixed by means of a screw 38 to the sole-plate 29. The rails are again held securely against the wedge-shaped piece 37 by 80 clips which are not shown.

In the case of pieces of track for railways which are not operated electrically but by steam or clockwork, it is not necessary for these fitting pieces to be made of an insulating material. They may instead be made of light metal, for instance of die castings or the like. The fitting pieces may also be made of a material which is easily tooled, for instance can be carved, so that older and more skillful boys can make the parts themselves.

What I claim is:

1. In a track for toy railways a fitting piece for switches and crossings, having raised parts and incisions adjacent to the said raised parts for the insertion of the rail ends, such that the rails are flush with the said raised parts at the switches and crossings, and means whereby the fitting piece can be screwed to and unscrewed from the sleeper or other support, as and for the purpose set forth.

2. In a track for toy railways a fitting piece made of pressed material for switches and crossings, having raised parts and incisions adjacent to the said raised parts for the insertion of the rail ends, such that the rails are flush with the said raised parts at the switches and crossings, and means whereby the fitting piece can be screwed to and unscrewed from the sleeper or other support, as and for the purpose set forth.

3. In a track for toy railways a fitting piece for switches and crossings, having raised parts and incisions adjacent to the said raised parts for the insertion of the rail ends, such that the rails are flush with the said raised parts at the switches and crossings, means whereby the fitting piece can be screwed to and unscrewed from the sleeper or other support and having side abutments for supporting the rails which do not end in the incisions of the fitting piece, but extend past them, as and for the purpose set forth.

4. In a track for toy railways a fitting piece for the pivotal points of switch blades, having raised parts and incisions adjacent to the said raised parts for the insertion of the rails ends, such that the rails are flush with the said raised parts at the switches and crossings, means whereby the fitting piece can be 130

screwed to and unscrewed from the sleeper or other support and two lateral abutment surfaces disposed with respect to one another at the entering angle of the branching-off 5 line for the outer rails and two depressions for the pivot pins of the switch blades, as and for the purpose set forth.

In testimony whereof I have signed my name to this specification.

10 FRIEDRICH OTTENSTEIN.
